D. D. CAMPBELL,
GRAIN DOOR,
APPLICATION FILED JUNE 14, 1920.

1,371,858.

Patented Mar. 15, 1921.

INVENTOR
DONALD D. CAMPBELL

or Fetherstonhaugh Co.
Mfg. Co.

UNITED STATES PATENT OFFICE.

DONALD D. CAMPBELL, OF WINNIPEG, MANITOBA, CANADA.

GRAIN-DOOR.

1,371,858.

Specification of Letters Patent. Patented Mar. 15, 1921.

Application filed June 14, 1920. Serial No. 388,910.

To all whom it may concern:

Be it known that I, DONALD D. CAMPBELL, a subject of the King of Great Britain, a resident of the city of Winnipeg, Province 5 of Manitoba, Dominion of Canada, have invented certain new and useful Improvements in Grain-Doors, of which the following is a specification.

This invention relates to improvements in 10 grain doors for railway freight cars, and the objects of the invention are to provide an extremely simple form of grain door which will not get out of order and which will prevent leakage of the grain in transit and 15 to facilitate loading and unloading of the cars.

Further objects are to provide a grain door that may be placed in position in sections and will remain in place without being 20 fastened to the sides of the freight car by nails, screws, or fastenings of any kind, and that may be removed at destination without damaging the door or the car in any way.

With the above and other objects in view, 25 the invention consists essentially of the construction described in detail in the accompanying specification and drawings.

In the drawings:

Figure 1 is a perspective view of an embodiment of the outside of the grain door.

Fig. 2 is a sectional perspective view of the same.

Fig. 3 is a horizontal section of the door.

Fig. 4 is a perspective view of one of the 35 sections of the same.

Like characters of reference refer to like parts on all the drawings.

Referring to the drawings, C and D represent the two lower sections of the door and 40 E and F the two upper sections of the door, the two lower sections being formed considerably wider than the upper sections, and all of the sections being rabbet jointed to each other but not being fastened rigidly 45 together.

These sections may be constructed in any convenient manner, the sections shown being formed of two thicknesses of boards, of such width and fastened together in such a 50 manner that each section overlaps the section immediately underneath for the space of two inches.

Each section is reinforced by a plurality of say three reinforcing supports or strips 55 10 at right angles to the bottom of the section in such a manner that the strips of each

section will be immediately above the strips of the section below, whereby the reinforcing strips will extend vertically from the top to the bottom of the car.

60

The edges of each strip are beveled in such a manner as to leave exposed the bottom of the strips reinforcing the sections immediately above so as to permit pressure being brought to bear on the bottom of such 65 strips for the purpose of removing the sections of the door.

The sections E and F are relatively wider than the sections C and D and these sections are provided with suitable retaining plates 70 G. These retaining plates are suitably supported from the side of the door and adapted to project over the ends of the sections.

One retaining plate G is provided on each side of the door and is formed in two sections, a lower portion, 11 and an upper portion, 12. The edges of the portion 12 are spaced back a distance from the edges of the portion 11, whereby the distance between the inner edges of the portion 12 will be 75 greater than that between the inner edges of the portion 11 of the plate G on opposite sides of the door. In this way, the sections C and D may be raised and lifted outwardly between the portions 12 without engaging 80 the said portions.

In this way it is possible to provide wider lower sections C and D since the limit to the width is the distance between the top of the portions 11 and 12 and the roof of the car.

90

In filling the car the sections are placed in position as indicated, the pressure of the grain holding the sections firmly in position against the side of the door opening. Should it be desired to inspect the car, the 95 top of the section F may be removed and a sample of the grain taken. When it is desired to empty the car, the sections may be successively disengaged by the use of a suitable lever or bar H which may be inserted to press on the reinforcing strips 10 which, when pried upwardly, will carry the sections with them.

As many changes could be made in the above construction and many widely different embodiments of my invention within the scope of the claim, constructed without departing from the spirit or scope thereof, it is intended that all matter contained in the accompanying specification and drawings 110 shall be interpreted as illustrative and not in a limiting sense.

2
What I claim as my invention is:

A grain door comprising upper and lower sections, the lower sections being wider than the upper sections, each section being
5 formed with a plurality of reinforcing strips correspondingly spaced on all the sections and having the edges beveled at one end to permit the application of pressure to the end of the strip on the adjacent
10 section, and a retaining means on the side of the car door including plates engaging the outer edges of the sections on opposite

sides thereof, the inner edges of the plates engaging the upper sections being a greater distance apart than those engaging the lower 15 sections, and sufficiently far apart to permit the lower sections to be withdrawn between the plates designed to engage the upper sections.

In witness whereof I have hereunto set my 20 hand in the presence of a witness.

DONALD D. CAMPBELL.

Witness:

RUSSEL S. SMART.
